TABLE TRAY

Nicholas Valos, Chicago, Ill.

Application November 30, 1953, Serial No. 27,845

Term of patent 14 years

(Cl. D33—14)

To all whom it may concern:

Be it known that I, Nicholas Valos, a citizen of the United States, residing at Chicago, in the county of Cook and State of Illinois, have invented a new, original, and ornamental Design for a Table Tray, of which the following is a specification, reference being had to the accompanying drawing forming a part thereof.

In the drawing:

showing the table tray compartments as they appear when opened.

I claim:

The ornamental design for a table tray, substantially as shown.
